UNITED STATES PATENT OFFICE.

JOHN D. CROCKER AND JUNIUS A. BRAND, OF NORWICH, CONNECTICUT.

IMPROVEMENT IN STRETCHERS FOR PICTURES.

Specification forming part of Letters Patent No. 119,507, dated October 3, 1871.

To all whom it may concern:

Be it known that we, JOHN D. CROCKER and JUNIUS A. BRAND, of Norwich, in the county of New London and State of Connecticut, have invented a new and useful Improvement in Stretcher-Braces for Picture-Frames; and we do hereby declare that the following is a full, clear, and exact description thereof, reference being had to the accompanying drawing making part of this specification, in which—

Figure 1 is a section through the ends of two frame pieces, showing the improved bracing-stretcher applied. Fig. 2 is a view of the mitered end of one of the frame pieces with the stretcher applied. Fig. 3 is a perspective view of the angular stretcher-brace. Fig. 4 shows the mitered ends of two frame pieces with a staple applied to them. Fig. 5 shows the mitered ends of two frame pieces applied inside of a frame, with a serrated wedge driven between the mitered ends. Fig. 6 is a perspective view, showing more clearly the notched wedge. Fig. 7 shows a form of stretcher-brace which is adapted for use with a cross-bar.

Similar letters of reference indicate corresponding parts in the several figures.

This invention is designed to facilitate the application of canvas to picture-frames for other purposes, and also to keep the canvas under constant and proper tension, and to prevent the frame from twisting.

The following description will enable others skilled in the art to understand our invention.

In the accompanying drawing, A A represent the mitered ends of a frame, which are mortised and bored out to receive a right-angular webbed bar, B, as shown in Fig. 1. The bar B may be round or flattened, and through its ends holes may be formed, as shown at a a, Figs. 1 and 2. This bar is constructed with two central webs, b c, which are thin, and are received into mortises or kerfs made into the frame pieces. The bars b are intended to form a union between the frame pieces at their angles or joints and to allow springs e e to be brought into play so as to force the frame pieces apart, as explained in the schedule annexed to the Letters Patent of JOHN D. CROCKER, numbered 106,332. The thin webs which are cast on these bars, and which are received into the mitered ends of the frame pieces A' A, are intended to prevent lateral displacement of the frame pieces, and also to prevent the frame from

twisting. The webs thus operate as braces to the frame and, at the same time, strengthen the bar or rib B at its angle. In Fig. 7 we have represented a webbed bar or brace, which is used in connection with a cross-bar that may be confined between two opposite frame pieces. This webbed bar differs from the device shown in Fig. 1 merely in shape, one being a webbed angular bar while the other is a webbed straight bar. When the webbed bars of Fig. 7 are used, their ends are inserted into the ends of the cross-bar and also into the inner edges of the frame pieces. When springs e e are used to force the frame pieces apart and keep the canvas stretched by the recoil of these springs, we employ staples g, the ends of which are inserted into the frame pieces for holding the springs compressed while the canvas is being tacked on the frame. After the canvas is applied to the frame the staples g are removed. Instead of the staples g pins may be inserted through the frame pieces and through the holes a a which are made through the bar B, as shown in Figs. 1 and 3. Where it is not desired to use springs to force the frame pieces apart we may employ wedges w, the tapered sides of which will be serrated, as at s, Fig. 6, to prevent displacement. These wedges will be driven between the mitered ends of the frame pieces from within outward after the canvas is tacked on the frame.

We do not, under this petition, lay claim to a right-angular tenon or bar having a flat plate on one side of it, as described in the Letters Patent numbered 106,332. We construct the bars or ribs with webs in such manner that both the bar and web are received into recesses made into the frame pieces, thereby providing a concealed brace which can be readily cast and applied to the frames. For oval or elliptical frames the bars or ribs B may be straight, or they may be of an angle greater than a right angle.

By reference to Fig. 5 it will be seen that we secure the stretcher-frame into an ornamental frame, F, by means of straight pins p, one of which is shown in the figure. This pin p is pointed to enter frame F readily, and it is inserted through a hole made through the stretcher-frame, which hole should be large enough to allow the frame A to expand and contract freely; otherwise the canvas will warp and become loose. The frame F may be secured into a gilt or other

finished frame, F', by means of buttons or other suitable devices; or the stretcher-frame A may be secured directly to the gilt frame by means of the long pins *p*.

Having described our invention, what we claim as new, and desire to secure by Letters Patent, is—

1. A metal plate consisting of a web and bar or rib, the former extending out centrally from the elongated spring-bearing rib or bar B, and the whole applied wholly within inclosed recesses of the frame, substantially in the manner and for the purpose described.

2. The combination of the braces, springs, and staples *g*, substantially in the manner and for the purpose described.

3. The pins *p* inserted loosely through holes made through the stretcher-frame for securing the stretcher-frame into the ornamental frame, substantially as described.

JOHN D. CROCKER.
JUNIUS A. BRAND.
